UNITED STATES PATENT OFFICE.

JULIUS S. FOX, OF CLEVELAND, OHIO.

BARRIER SHOE FOR AEROPLANES.

Application filed September 27, 1926. Serial No. 137,891.

This invention relates to barrier shoe for aeroplanes, and is especially designed to serve as a means of obstructing the forward advance of an aeroplane or other aerial vehicle while the latter is increasing the speed of its engine and propeller until, having accumulated sufficient reserve power by attaining proper speed, said barrier may be readily and quite suddenly released, and the vehicle 5 permitted to rush forward with high speed, using such accumulated force or power which has been thus attained, because of entire lack of retardation by the usual extremely gradual increase of speed of the 10 vehicle, which results from air obstruction prior to the moment when the engine has attained sufficient speed, and from the difficulty of overcoming the momentum of the 15 vehicle and its load while yet the force of the propeller is not great enough to overcome it.

It is therefore an object of my invention to provide a floor means with a shoe member hinged thereto upon a transverse hinge, 25 so that an actuator connected to the shoe leads backward of the vehicle which rests upon the floor element while the engine is starting, and may, when proper engine speed is attained, suddenly remove the shoe 30 as an effective barrier from the floor support, and permit the advance of the vehicle.

With these and other objects in view, I have incorporated my invention in an illustrative embodiment of the same which is 35 described hereinafter, recited in the appended claims, and illustrated in the accompanying drawings, in which—

Figure 1 is a side view in elevation of my barrier shoe and mounting mechanism with 40 an aeroplane shown in position thereon;

Figure 2 is a plan view of the same;

Figure 3 is a side elevation of the frame mechanism for the shoe, but with the barrier shoe in vertical, central, longitudinal section, and mounted in a manner slightly modified from that shown in Figs. 1 and 2, and

Figure 4 is a front elevation of the device shown in Fig. 3.

My invention is here shown as mounted upon what may be a launching stage, a repair floor, or a testing platform, the floor 5 of which may be anchored upon an outdoor space which may be level ground or uneven ground, in which latter case suitable piles 55 may be provided to positively support the

stage. This floor 5 may be so anchored for more readily taking off of the plane therefrom or for supporting the plane in a repair shop to hold the same in position while the 60 propeller is actuated at high speed to enable careful observation of the plane, propeller and engine while so running.

Upon the forward portion 7 of the platform or floor 5 is mounted fixedly an inclined support floor 8 whose rear end 9 is attached to the floor 5 and the front edge 10 supported in a position quite a little higher than the horizontal surface of the base floor 5. To this edge 10 is hinged by a transverse pin 11 the barrier shoe 12 which is usually of polygonal shape and is hinged at 11 upon one of its sides or longest edges. The opposite or outer edge 13 of this shoe 12 has secured thereto a strengthening bar 70 or brace 14 whose ends 15 extend laterally from said shoe a short distance for a purpose later to be explained.

Upon the side edges 16 of said shoe are fixed brace blocks 17 near the hinge edge 80 thereof, and fixed upon these blocks 17 are bars 18 positioned at right angles to the plane of the shoe and to the edges bearing the blocks 17. These arms or bars 18 are spaced somewhat from the lower or hinge edge of the shoe for the purpose of actuation of the latter. A cable element 19 is attached to the edge 13 of the shoe at each side by fixing the same to the ends 15 respectively. The cable ends are then directed backwardly above and below the ends of the bars 18 on either side, and thence wound about a reel 20 which is mounted for rotation transverse of the rear end of the floor 5, and is provided with a crank for actuation, so 95 that rotation of the reel will actuate the bar ends and with them the edge 13 of the shoe to lift or lower the shoe on such hinge 11. 100 To determine the effectiveness of the shoe 12 as a barrier.

In Figs. 1 and 2, the barrier shoe 12 has been shown as inclined, which arrangement is satisfactory, when the shoe leads forward to an adjoining, inclined platform 21. In Figs. 3 and 4, however, the shoe 12^a is shown 105 as substantially horizontal when in the lower position, and is most practicable when the shoe leads forward to a horizontal platform 21^a. The general structure of the two forms of barrier shoe is in the main very similar, and the actuation thereof is substantially identical. The bar 14 as well as the blocks 17

and actuating bar 18 are quite similar in use on the different forms of shoes—12 and 12^a.

Operation: If an aerial vehicle 22 is to be launched from the floor or staging 5 out upon the inclined platform 21, the latter, if movable, is brought into register with the shoe 12, the latter being in the lower position shown in Figs. 1 and 2. The plane, as 22, is then positioned with its supporting 10 wheels resting upon the inclined platform 8 and the rear end supported upon the main floor 5 just forward of the reel or pulley shaft. Since there are two pulleys 20 on this shaft, the plane may readily be placed between these pulleys. The shoe 12, or 12^a if this form is used, is now raised on the hinge pin 11 to an angle desired, this being dependent more or less upon the weight of the vehicle, its power, and the speed to be attained 20 (of the engine and propeller, not necessarily of the vehicle itself), before the vehicle is permitted to rush forward, first upon the platform 21, or 21^a, and then in aerial flight.

The shoe is retained in the upper position 25 to act as a positive barrier to the forward advance of the vehicle until the desired propeller speed is attained, after which the cable 19 is actuated by means of the parts 13 to 18 and 20, to suddenly lower the shoe to release the plane from its barrier. It is a 30 special advantage of my construction that such release does not require the operator to be beneath the plane but is stationed at the rear thereof, avoiding danger of accident when the plane is retained while the engine is running, as well as after its release. The part 21^a may be a horizontal platform to receive the vehicle upon its release, or it may 35 be a short base plate for receiving the wheels 40 of the vehicle thereon temporarily in positioning the same for testing, for example.

It is further to be observed that my improved construction is adapted for retaining the vehicle behind the barrier shoe while 45 running the engine short periods for observation and testing the same. Such floor 5 with the incline 8 and the barrier shoe may advantageously be installed in a repair shop or factory for observation, though not connected with any flight platform, and not used 50 there for more than temporary testing. For this purpose, though, the structure is very useful.

The relative width of the shoe compared 55 with the height of the vehicle wheels, is not intended to be limited to that shown in the drawings, but may be of any convenient width to produce the effective height when raised, as may be required.

Having now described my invention what I claim and desire to secure by Letters Patent of the United States is as follows—

1. A barrier shoe comprising a flat plate having hinge members on one of its longer edges; a brace block secured to one of the

shorter edges of the plate and a cross bar fixed upon the extreme end of said block, a brace member secured to the edge of the plate opposite the hinge members and extending slightly beyond the outline of the plate, and bracing cable members connecting the ends of said cross bar with the extended end of the brace member.

2. Barrier mechanism for aeroplanes comprising an elongated support platform having 75 a flat section and a front section inclined upwardly from the rear in fixed relation, a flat surfaced shoe hinged to the forward edge of said inclined section on a transverse axis for oscillating movement upwardly to 80 a position above the level of said front section, and means, including a winding element mounted transversely of the platform at its extreme rear end, and an actuating connector between the winding element and 85 shoe, for actuating the latter upon its hinge.

3. Barrier mechanism for aerial vehicles comprising a fixed supporting platform having 90 an upwardly-inclined forward section in fixed relation to the main platform, a shoe plate hinged to the forward edge of said inclined section on a transverse axis, a transverse block extending laterally from the shoe 95 at a point adjacent the hinge, a bar mounted on said block at an angle to the plane of the shoe and block, a cable element secured to the forward part of said shoe and guided by the ends of the bar, and extending rearwardly to a point on said platform beyond 100 the intersection of the platform and inclined section, and means at said point for actuating said cable element to move the shoe plate on said hinge.

4. Barrier mechanism for aeroplanes comprising a support platform, an inclined forward section inclined upwardly from an intermediate part of the platform and in fixed relation thereto, a barrier shoe plate hinged to the forward edge of the inclined section for pivotal movement on a transverse axis, 110 fixed brace means supported upon said main platform forward of the hinge, to receive thereon the forward end of the shoe when the latter is in its lower position, a transverse winding element mounted for rotation or 115 oscillation at the rear end of the platform, means for actuating said element, an endless cable element attached to the forward end of the shoe and passing over the winding element, and means attached to said shoe plate 120 at its lateral edges for separating the two strands of said cable element as they pass rearwardly over the hinge, so that actuating means will swing the shoe plate upwardly to present a barrier to the advance of a vehicle resting on said inclined section, and remove said barrier when the shoe is lowered.

In witness whereof I have hereunto set my hand this 22nd day of September, 1926.

JULIUS S. FOX.
